UNITED STATES PATENT OFFICE

111,797

DESIGN FOR A CASTING BAIT

Chester D. Stickrath, Dayton, Ohio

Application March 11, 1938, Serial No. 75,766

Term of patent 7 years

To all whom it may concern:

Be it known that I, Chester D. Stickrath, a citizen of the United States, residing at Dayton, Montgomery County, Ohio, have invented a new, original, and ornamental Design for a Casting Bait, of which the following is a specification, reference being had to the accompanying drawing, forming a part thereof, in which Fig. 1 is a perspective view of a casting bait embodying my new design.

Fig. 2 is a side elevation thereof.

Fig. 3 is a top plan view.

Fig. 4 is a front elevation.

The casting bait design herein illustrated is of fanciful form and grotesque appearance in exaggerated arbitrary simulation of an insect, and in practice is of variegated colors. The shading is to indicate surface contour and contrast of colors.

I claim:

The ornamental design for a casting bait, substantially as shown and described.

CHESTER D. STICKRATH.
